UNITED STATES PATENT OFFICE.

ENOCH CHINSTRAND, OF MOHAWK, NEW YORK, ASSIGNOR TO LIBRARY BUREAU, OF CAMBRIDGE, MASSACHUSETTS, A CORPORATION OF NEW JERSEY.

CABINET.

Application filed January 28, 1922. Serial No. 532,448.

To all whom it may concern:

Be it known that I, ENOCH OHNSTRAND, citizen of the United States of America, and resident of Mohawk, in the county of Herkimer and State of New York, have invented new and useful Improvements in Cabinets, of which the following is a specification.

This invention relates to cabinets and particularly to fire resistant cabinets such as vaults, safes, filing cabinets, etc., designed for the protection of documents and other valuables from fire.

When cabinets are subjected to intense heat, as in a fire, the expansion of the metal resulting from the heat followed by contraction as the cabinet cools more or less rapidly frequently causes distortion and deformation of the cabinet walls. This is most serious when it occurs in the door frame and sides adjacent the door where it usually opens up the crack between the door and door frame permitting heated air, gases, smoke, steam, water and sometimes flame to reach the interior of the cabinet to the injury and perhaps destruction of the contents.

Objects of the invention are to restrain deformation of fire resistant receptacles, to maintain close contact between the doors and door frames of such structures, to strengthen the latter against strains due to expansion and contraction and against shocks due to falls, and in general to improve devices of this kind.

The invention comprises means for maintaining an inward pressure upon the door frame of a fire resistant cabinet to oppose outward deformation of the frame. It further comprises protecting said means from heat. Means are provided for reenforcing the frame where the pressure is applied. Both said means are preferably incorporated in a truss structure comprising an elongate member attached to the frame with a projecting member or spacer intermediate its ends and a truss rod bearing upon said spacer. The ends of the truss rod are suitably anchored and preferably have end supports bearing upon the outer casing of the cabinet. Means are provided for insulating the truss rod from heat as by embedding it in the heat insulating filling of the cabinet.

In order to illustrate the invention one concrete embodiment thereof is shown in the accompanying drawings, in which,—

Figure 1 is a front elevation of a safe showing in dotted lines truss structures at the top and bottom thereof;

Figure 2 is a fragmentary view of the upper and lower portions of the safe, the center being cut away, and showing the truss structures in full lines and the adjacent parts of the safe in dotted lines;

Figure 3 is a section on the line 3—3 of Fig. 2;

Figure 4 is an end elevation of the lower truss structure; and

Figure 5 is a section on the line 5—5 of Fig. 2.

The embodiment of the invention shown for the purpose of illustration comprises a safe A having an angle iron frame B, swinging doors C pivoted to the frame at D, lock dial E and bolt operating handles F. As indicated in Fig. 3 the safe has an outer casing G and an inner casing H, the inner casing forming the door jamb. The space between the two casings is filled with heat insulating material I. In order to prevent the opening or widening of the crack between the door and door jamb, which frequently happens either during expansion of the wall of the safe from heat during fire or from contraction following the fire, truss members are provided to maintain the door jamb in proper position. In the drawing the safe is shown as provided with truss structures at the top and bottom only but it is obvious that such structures may be used at the sides also if desired. The truss structures are similar in form but reversed in position and have as a base a flat bar 6 having integral angularly disposed flanges 7 at its ends.

Bar 6 is attached in a suitable manner to the inner face of a wide portion of the door jamb as indicated at 8, Fig. 3, as by screws 9, Fig. 2, and serves as a reenforcement for the door jamb at this point. Centrally disposed on the bar 6 is a projection or spacer member 10 in the form of an angle iron, one flange of which is fast to bar 6. With its central portion disposed upon spacer member 10 and its ends extending through openings in the flanges 7 of bar 6 is truss rod 11. On the projecting ends of the rod 11

are end supports 12 having portions 13 adapted to bear against outer casing G as shown in Fig. 3. Truss rod 11 may be tensioned to produce downward pressure upon 5 bar 6 through spacer 10 by tightening nuts 14 on the ends thereof. By reason of the slight inclination of the portion of the door jamb to which the bar 6 is attached, the edges of flanges 7 are angularly disposed to 10 the corresponding edges of end supports 12 as indicated in Figs. 3, 4 and 5. The truss structures at the top and bottom of the safe are reversed in position to apply the proper pressure to their respective portions of the 15 door jamb, as indicated in Fig. 2. By disposing the truss structures to bear upon the broad section 8 of the door jamb the truss rods are spaced a sufficient distance from the outer casing G to protect them from 20 heat, which is accomplished by imbedding them in and entirely surrounding them with the heat insulating material I. This insulation from heat is essential to the proper functioning of the truss structures since 25 expansion of the truss rods under heat would destroy the tension therein and outward bulging of the door jamb under expansion would no longer be sufficiently resisted.

I claim:

- 30 1. In a cabinet having an opening and a door frame in said opening, means maintaining constant inward pressure on said frame for preventing outward bulging of the sides of said frame in the plane of the opening.
- 35 2. In a fire-resistant cabinet having an opening and a door frame in said opening, means maintaining constant inward pressure on said frame for preventing outward bulging of the sides of said frame in the plane 40 of the opening, and means for protecting said means from heat.
- 45 3. In a cabinet having an opening and a door frame in said opening, means for reenforcing said frame, and means for maintaining constant pressure on both said frame and said reenforcing means, said pressure being applied in a plane substantially perpendicular to said reinforcing means.
- 50 4. In a cabinet having an opening and a door frame in said opening, means disposed substantially perpendicularly to said reinforcing means for reenforcing said frame, and means for opposing outward distortion of both said frame and said reinforcing 55 means, said opposing means being insulated from heat.
- 60 5. In a cabinet having an opening and a door frame in said opening, a truss structure associated with said frame for opposing outward bulging of the sides thereof, said structure being constructed and arranged to apply pressure to the sides of said frame in a plane substantially perpendicular to said sides.
- 65 6. In a fire-resistant cabinet having an

opening and a door frame in said opening, a truss structure for reenforcing said frame and opposing outward bulging of the sides thereof, said structure being protected from heat and arranged to maintain a constant inward pressure on said frame substantially in the plane of said opening. 70

7. In a cabinet having an opening and a door frame in said opening, a truss structure comprising an elongate member adapted to be made fast to said frame, and truss means on said member for opposing outward distortion of the sides of said frame in the plane of said opening. 75

8. In a cabinet having an opening and a door frame in said opening, a truss structure comprising a reenforcing member for said frame fast thereon, a truss rod attached at its ends to the ends of said member, and a spacer disposed intermediate the ends of said member for tensioning said rod. 85

9. A fire-resistant cabinet having inner and outer casings, heat insulating material between said casings, a door opening, a door frame in said opening, and means embedded in said heat insulating material for opposing outward distortion of the sides of said frame in the plane of said opening. 90

10. A fire-resistant cabinet having inner and outer casings, heat insulating material between said casings, and a truss structure embedded in said heat insulating material for opposing outward distortion of the sides of said frame in the plane of said opening. 95

11. A cabinet having inner and outer casings, heat insulating material therebetween, said cabinet having an opening with a frame therein, a reenforcing member fast on said frame, and a truss structure attached to said member and embedded in said heat insulating material for opposing inward distortion of the sides of said frame in the plane of said opening. 100

12. A cabinet having an inner and outer casings, said cabinet having an opening provided with a door frame, a reenforcing member fast on said frame having a spacer intermediate its ends, and a truss rod fast at its ends to said member and bearing upon said spacer. 105

13. A cabinet having an inner and outer casings, a door frame for said cabinet, a truss structure for opposing outward distortion of said frame, and end supports for said structure bearing upon said outer casing. 110

14. A fire-resistant cabinet having inner and outer casings, a door frame for the cabinet, a reenforcing member fast on said frame, a truss rod bearing upon said member, and end supports for said rod bearing against said outer casing, said rod being embedded in said heat insulating material. 115

15. A cabinet having inner and outer casings and a door frame, an elongate member fast on said frame having integral angular 120

larly bent ends and a spacer intermediate its ends, and a truss rod fast in openings in said ends and bearing upon said spacer.

16. A fire-resistant cabinet having and 5 outer casings and a door frame, an elongate member fast on said frame having integral angularly bent ends and a spacer intermediate its ends, a truss rod fast in openings in

said ends and bearing upon said spacer, and end supports for said rod bearing against 10 said outer casing, said rod being embedded in said heat insulating material.

Signed by me at Mohawk, N. Y., this 24th day of January, 1922.

ENOCH OHNSTRAND.

Certificate of Correction.

It is hereby certified that in Letters Patent No. 1,442,732, granted January 16, 1923, upon the application of Enoch Ohnstrand, of Mohawk, New York, for an improvement in "Cabinets," errors appear in the printed specification requiring correction as follows: Page 2, line 109, claim 12, and line 116, claim 13, strike out the word "an"; same page, line 127, claim 14, strike out the word "said"; page 3, line 4, claim 16, after the word "having" insert the word *inner*; same page and claim, line 12, strike out the word "said": and that the said Letters Patent should be read with these corrections therein that the same may conform to the record of the case in the Patent Office.

Signed and sealed this 27th day of February, A. D., 1923.

[**SEAL.**]

KARL FENNING,

Acting Commissioner of Patents.
